SYSTEM FOR AUTOMATIC COIL WINDING
MACHINES

Gilbert C. Holloway, Bloomfield, N. J., assignor,
by means assignments, to Westinghouse Electric
and Manufacturing Company, East Pittsburgh,
Pa., a corporation of Pennsylvania

Application April 29, 1933, Serial No. 668,533

5 Claims. (Cl. 177—311)

My invention relates to coil winding machines and particularly to such machines of the mandrelless type as employed in the making of filaments for incandescent lamps wherein a visual indication is given to an operator and the machine automatically stopped upon the occurrence of any faulty operation of the machine.

In machines of this general character the filament is wound in the form of a helix having convolutions of the desired diameter and pitch and cut in predetermined lengths as the completed filaments are discharged by the machine at a uniform rate. During operation of the machine it is not an infrequent occurrence for the wire to accidentally become tangled in some manner in the machine or become disengaged from the die or guide rollers. In an instance of this kind continued operation of the machine aggravates this condition resulting in a loss of time and perhaps a breaking of the filamentary wire unless the operator should happen to immediately notice the occurrence of the faulty operation of the machine.

By my present invention I minimize these contingencies by the provision of a coil winding machine wherein the machine is automatically stopped and a visual indication given to the operator upon the occurrence of any fault in the operation of the machine. This not only leads to economical operation of the machine itself but makes it possible for a single operator to operate several machines simultaneously.

For a better understanding of my present invention reference may be had to the accompanying drawings wherein,

Figure 1 is an elevational view of one type of coil winding machine constructed in accordance with my present invention showing a convenient disposition of the various elements, and

Figure 2 is a diagrammatical representation of the fault indicating system of the machine shown in Figure 1.

Referring now to the drawings in detail I have shown in Figure 1 a coil winding machine of the mandrelless type such as shown and claimed in U. S. Patent No. 1,670,499 issued May 22, 1928 to J. W. Ekstedt. The machine shown in the above patent includes a suitable electric motor driving a coil winding die 1 usually consisting of a diamond having an arcuate cavity disposed in the path of movement of a filamentary wire fed from a spool 2 and over a guide drum 3. The wire issues from the die in the form of a continuous coil and is severed into sections 4

by a suitable cutter adjacent to the die. The coiled sections are of such length as to constitute lamp filaments. The lengths of these sections may vary depending upon the wattage of the lamp in which they are to be used. The coiled sections 4 are driven out by the force of the coiling action and discharge through a chute 5 into a receptacle 6 at a predetermined uniform rate.

In the event that some fault occurs which causes too great a variation in the rate of discharge of the filamentary coils 4 or they cease altogether due to exhaustion of the wire from the spool 2 the operation of the machine is automatically interrupted.

I accordingly provide an insulating member, such as a cylinder 7 of bakelite, hard rubber, glass or the like in the chute 5. A pair of concentric metal cylinders forming contactors 8 and 9 are disposed within the insulating member 7 in such a manner that they are insulated from each other and from the metal chute 5, but are positioned to allow the coiled filaments to pass therethrough as they are discharged from the machine into the receptacle 6.

Accordingly the completed filament in passing from the machine through the chute 5 to the receptacle 6 must necessarily establish an electrical contact with the contact terminals 8 and 9. The contact of the coiled filaments is intermittent but at a definite rate thus making the interim between contact of successive filamentary coils of very short duration. I connect an electrical circuit to these contact members 8 and 9 which comprises a suitable source of electrical energy, such as a series of batteries 10, the negative terminal of which is connected through a conductor 12 to the contact terminal 9. The positive terminal of this source 10 is connected by means of a conductor 13, to one end of an adjustable high resistance element 14 and the remaining end of this resistance is connected to a junction 15. A second low resistance element 16 has one of its ends connected to this junction 15 while its remaining end is connected, by means of a conductor 17 to the contact terminal 8.

A condenser 18 has one plate thereof connected by means of a conductor 19 to the junction 15 while its remaining plate is connected through a conductor 20 to the conductor 12 and thus to the negative terminal of the source 10.

This condenser 18 accordingly forms a shunt circuit with the source 10 and the filamentary coils as they successively establish contact with the terminals 8 and 9 and being permanently

connected to the source 10 is continually charged by the latter at a value determined by its respective capacity and the high resistance element 14. On the other hand the inclusion of the 5 filamentary coils in the circuit, as they are discharged from the machine, is intermittent and during the short interim when no filament completes a circuit between the contact terminals 8 and 9 all the energy of the source is supplied to 10 the condenser 18.

If this interim is of too long a duration the condenser 18 will become charged to a potential of predetermined magnitude, but when of short duration, determinable by the adjustable resistance 14 and the capacity of the condenser itself, the condenser discharges through the resistance element 14 and filamentary coils 4 as the latter intermittently establish contact with the contactors 8 and 9. The condenser 18 is thus prohibited from becoming charged to its potential of predetermined magnitude with the resistance element 16 functioning not only to assist in the dissipation of the condenser discharge, but also to prevent sparking at the contact terminals 8 25 and 9 as the circuit is made and broken by contact of successive coils 4. Accordingly upon a cessation of the discharge of the filamentary coils 4 from the machine, or too great a time lapse between successive coils, the condenser becomes 30 charged to the potential of predetermined magnitude and in order to give an indication of this condition to an operator as well as cause an interruption to the operation of the machine I connect the starting anode of a discharge device 22 to the junction 15 and accordingly to the positive terminal 35 of the condenser 18 by means of a conductor 23.

This discharge device is of a type well known in the art as having a critical breakdown characteristic. When the potential upon the starting anode rises to a certain value ionization of the gas within the tube occurs and causes a breakdown thereof thus enabling a current to flow in the output circuit which is connected to 45 the main anode and cathode of the device.

A conductor 24 connects the cathode of the device 22 to the negative terminal of the source 10, or conductor 12 extending from the latter, and the anode of this device is connected by 50 means of a conductor 25, to one end of the winding of a relay 26. The other end of this relay winding is in turn connected by a conductor 27 to the positive terminal of the source 10, but is adapted to be interrupted by a normally closed 55 spring pressed push button switch 28. This switch is in turn provided with a pair of normally open contact terminals 29 and 30, with the terminal 29 connected by means of a conductor 32 to the conductor 12 and thus to the negative 60 plate and terminal of the condenser 18 and source 10, respectively, while the remaining terminal 30 is connected by means of a conductor 33 to the conductor 17 and accordingly to one end of the resistance element 16.

65 It thus becomes obvious that with the switch 28 in its normal position a positive polarity is supplied from the source 10, through conductor 27 and switch 28, winding of relay 26, and conductor 25 to the anode of the discharge device 22 and that a negative polarity is supplied by the source 10, through conductors 12 and 24, to the cathode thereof. No current will flow at this time, however, through the circuit as the discharge device has not broken down and 70 is consequently in the "opened" position.

Moreover, the starting anode is supplied with a positive polarity from the junction 15, which is connected to the positive plate of the condenser 18, but this potential is not of sufficient magnitude to cause ionization of the gas within the device or breakdown thereof, due to the periodic discharging of the condenser 18, as previously explained, thus preventing the potential from rising to the predetermined magnitude.

Should, however, there be too long an interim between the intermittent engagement of the filamentary coils with the contact terminals 8 and 9, which enables the condenser to become more highly charged to the potential of predetermined magnitude the potential impressed upon the starting anode by the condenser 18 naturally rises. This rise of positive potential upon the starting anode increases the potential difference between it and the cathode, which has a negative polarity also impressed by the condenser 18, and immediately causes an ionization of the gas within the device. Upon ionization of the gas by the increased potential on the starting anode the device will break down thus "closing" the same by enabling electrons to flow between the main anode and cathode thereof with attendant current flow in the output circuit with energization of the relay 26.

The relay 26 is provided with a pivoted contactor 34 connected to the core thereof which in the normal deenergized position of the relay winding establishes a contact with a stationary contact terminal 35 and in its energized position establishes contact with a similar stationary contact terminal 36.

The pivoted contactor 34 is electrically connected to one side of the source for supplying energy to the motor of the coil winding machine and the contactor 35, which is normally engaged by the pivoted contactor, is connected to one side 40 of the armature and field of the motor thus permitting energization of the motor and operation of the machine when the usual motor controls are actuated.

Upon energization of the relay 26 following 45 break down of the device 22 the core of the relay is attracted causing opening of the contactors 34 and 35 and interruption of the motor circuit with a stopping of operation of the machine. At the same time contact will be established between the contactors 34 and 36 which 50 completes a circuit to an indicating lamp to give a visual indication simultaneously with stopping of the machine that due to some fault within the machine the completed filamentary coils are 55 not coming out of the machine at the predetermined rate.

After interruption of the operation of the machine has occurred and the indicating lamp has been lighted, the operator after rectifying the 60 fault in the operation of the machine must first depress the push button 28 before the machine can be again started. This interrupts the circuit to the relay 26 and discharge device 22, and also establishes contact with the contact terminals 29 and 30 thus enabling the accumulated charge of the condenser to be dissipated through the resistance element 16 by connecting the latter directly to the plates of the condenser. This accordingly resets the entire machine in condition 65 for reoperation.

In Figure 1 I have shown the various elements of the fault indicating portion of my present invention conveniently located at various positions of the machine which lends itself to compactness 70

and economy. As a matter of illustration the various elements may be located in the manner indicated by the descriptive legends shown in Figure 1, or otherwise conveniently positioned as desired. Moreover, while I have shown and described my invention as pertaining to a coil winding machine of the mandrelless type, as shown and described in the aforementioned patent, it is to be understood that the same is adaptable with equal facility to other types of machines.

Although I have shown and described one specific embodiment of my invention I do not desire to be limited thereto as various other modifications of the same may be made without departing from the spirit and scope of the appended claims.

What is claimed:

1. The combination with a coil winding machine for winding a filamentary wire into helically formed sections and intermittently discharging the same at a uniform rate, of means for discharging said helically formed sections from said machine in a predetermined path, and means provided with a portion thereof disposed in the path of discharge of said helically formed sections and intermittently contacted by said sections during discharge thereof and operable in response to a cessation of discharge of said helically formed sections for an abnormal period of time to cause a cessation of the operation of said machine.

2. The combination with a coil winding machine for helically winding a wire to form a filament for incandescent lamps and intermittently severing said wire into sections of predetermined length at a uniform rate, of means for successively discharging said filamentary sections from said machine in a predetermined path, means disposed in the discharge path of said filamentary sections and intermittently contacted thereby during their movement, and means connected to said last mentioned means and operable in response to an abnormal intervening interval between successive discharges of said filamentary sections to cause a cessation of operation of said machine.

3. The combination with a coil winding machine for winding a filamentary wire into helically formed sections and intermittently discharging the same at a uniform rate, of means for successively discharging said helically formed sections from said machine in a predetermined path, means disposed in the path of discharge of said helically formed sections and intermittently contacted thereby during their movement, and an electrical circuit connected to said last mentioned means and operable in response to an abnormal intervening interval between successive discharges of said helically formed sections to cause a cessation of the operation of said machine.

4. The combination with a coil winding ma-

chine for winding a filamentary wire into helically formed sections and intermittently discharging the same at a uniform rate, of means for successively discharging said helically formed sections from said machine in a predetermined path, means disposed in the path of discharge of said helically formed sections and intermittently contacted thereby during their discharge through said predetermined path, an electrical circuit connected to said last mentioned means including a source of electrical energy and an energy storage device energized from said source and operable to discharge its accumulated energy through said helically formed sections as the latter intermittently contact said last mentioned means at a uniform rate during their discharge from said machine, and a second electrical circuit including a device connected to the source of motive power for said machine and a device connected to said energy storage device and energized by discharge thereof upon the occurrence of an abnormal intervening interval between successive discharges of said helically formed sections from said machine, to cause current flow in said second mentioned circuit with attendant interruption to the source of motive power for said machine and a cessation of the operation of the latter.

5. The combination with a coil winding machine for winding a filamentary wire into helically formed sections and intermittently discharging the same at a uniform rate, of means for successively discharging said helically formed sections from said machine in a predetermined path, means disposed in the path of discharge of said helically formed sections and intermittently contacted thereby during their discharge through said predetermined path, an electrical circuit connected to said last mentioned means including a source of electrical energy and a condenser charged by said source and operable to discharge its accumulated energy through said helically formed sections as the latter intermittently contact said last mentioned means at a uniform rate during discharge from said machine, a second electrical circuit including a relay connected to a source of motive power for said machine and a discharge device connected to said condenser and energized by discharge thereof upon a cessation of discharge of said helically formed sections for an abnormal period of time to cause current flow in said second mentioned circuit with attendant energization of said relay and interruption to the source of motive power for said machine, and a cessation of operation of the latter, and a third electrical circuit adapted to be completed by operation of said relay simultaneously with the interruption of the source of motive power for said machine to give an indication to an operator of a cessation of operation of said machine.

GILBERT C. HOLLOWAY.
